UNITED STATES PATENT OFFICE.

ROBERT A. MOORE, OF NEW YORK, N. Y., ASSIGNOR TO MULTIPLE SELLING CORPORATION, OF NEW YORK, N. Y.

SAFETY LAMP LOCK.

Application filed February 7, 1928. Serial No. 252,492.

This invention relates to safety lamp locks.

One object of this invention is to provide an improved device to lock a lamp in its socket and prevent unintended or unauthorized removal of the same.

Another object of the invention is to provide a device of the character described in which improved means permits the said device to be unlocked.

10 A further object of the invention is the provision of a device of the type specified which includes a member having biting engagement between the socket and the lamp base, for the purpose set forth.

15 A still further object of the invention is the production of a device of the class described, which can be made as a simple stamping having improved coaction with the socket and lamp base.

20 Still another object of the invention is to furnish a device of the species mentioned which is neat and inconspicuous, so as to be inaccessible for unlocking except by a particular key or means; and which is of properly insulated character; and is reliable and efficient to a high degree in use.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a view in elevation of a lamp and socket assembly showing in section an embodiment of the invention in unlocked position.

Fig. 2 is an enlarged sectional view taken on the line 2—2 of Fig. 1.

Fig. 3 is a fragmentary view similar to Fig. 1 of the device in locked position.

Fig. 4 is an enlarged sectional view taken on the line 4—4 of Fig. 3.

Fig. 5 is an enlarged sectional detail view of the device in locked position.

50 Fig. 6 is a perspective detail view of a member embodying the invention.

Fig. 7 is a diagrammatic view showing the action of the locking member.

* Figs. 8 and 9 are fragmentary detail views 55 of modifications of the invention.

Referring in detail to the drawing, 10 denotes a lamp and 11 a socket, in conjunction with which this invention is embodied. The lamp is seen to comprise the usual screw base 12, having the end and shell contacts 13 and 14 respectively. Coacting with these, the socket has central and shell contacts 15 and 16. Between the shell 16 and the casing 17 of the socket, is inserted the usual sleeve of insulation 18.

Associated in an improved manner between the contact shells of the socket and lamp base is a lock 19 embodying the invention. This lock is of flat cross section and circular in formation, and can be made of various materials, 70 as, for example, steel or a softer metal. Preferably, the lock is made as a stamping bent to the desired form. Being of sufficient thinness, the same can be readily slipped into place in the socket without in any way interfering with the insertion of the lamp base thereinto, and its narrowness permits it to be sprung in a direction widthwise of the metal for releasing the lock as hereinafter described.

The device 19 includes a holder portion 20 having at its ends the lugs 21 which extend in the same direction and lie in the cylindrical surface defined by the device 19. Offset at 22 in the opposite direction is the shank portion 23, which lies between planes parallel to those of the holder portion 20. At the free end 24 of the shank portion, extending upward therefrom and in the direction of the lugs 21, is a locking member 25, and directly opposite thereto a retractor or engagement portion 26. The latter terminates in a laterally extending lug 27 which in the locking position of the device seats on the exposed edge of the insulation 18 as shown in Fig. 3. The retractor 26 is insulated preferably by immersing in a 95 bath of liquid insulating material and drying thereafter.

The locking member 25 is offset inward of the lock 19 as shown at 28 to be adapted to lie within the socket shell 16. It is also of transverse angularity with respect to the adjacent shank portion 24, and of ogee form, so that its side edges 29 and 30 are directed respectively inward and outward. The said edges are, likewise, comparatively thin, and the end 31 of the locking member is beveled down toward the edge 30 for a purpose hereinafter described.

In practice the device 19 is inserted coaxially into the socket, with the lugs 21 leading 110

into the relatively small space between the socket shell 16 and the sleeve of insulation 18, and facilitating the entrance of the holder 20 thereinto. The shank 23 then lies beyond 5 or under the lower edge of the shell 16, and seats circumferentially against the insulation 18. The locking member 25 is disposed within the socket shell 16, while the retractor 27 abuts the lower edge of the insulating sleeve 10 18.

A lamp base can now be freely screwed into the socket, the wall of the lamp base riding easily over the inclined, inner face of the locking member 25. The retractor 27 is now 15 small and inconspicuous at the side of the lamp.

Should an unauthorized person attempt to unscrew the lamp, the locking member 25 will bite at its edges 29 and 30 into the lamp and 20 socket shells 14 and 16 respectively, and prevent the lamp from being stolen. To this end the acute corner at the intersection of the edges 29 and 31 of the locking member will 25 co-operate by insuring an immediate grip of the safty device on the lamp base.

To open the locking device 19, a key adapted to engage the lug 27, is used to draw the retractor 26, and release the locking member 25. The said key may be of any suitable construction and is therefore not shown. It will 30 be understood that the shank 23 is sprung widthwise to release the locking member, and the latter is then positioned directly between the insulation 18 and the shell 14, and beyond 35 or below the shell 16. The lamp can now be unscrewed from the socket in the usual manner.

The device 19 can not be released except with a proper key provided for the purpose. 40 According to the construction of this invention, when a lamp has been screwed into its socket, the device 19 adjacent to the locking member will be frictionally engaged with sufficient tightness to prevent the retractor 45 from being operated except by the key aforesaid.

Fig. 8 illustrates a modification of the invention, wherein the retractor 26^a terminates in an eye portion 32, which is straight therewith, and extends alongside the lamp 10. The eye portion is small and inconspicuous, and is insulated by immersion in a solution of insulating liquid, that dries to form a coating thereon.

55 Fig. 9 illustrates a modified retractor 26^b that is straight throughout and is weakened at a series of notches 33. Should the depth of the lamp socket be less than usual, a portion of the retractor can be cut off at a notch 60 to shorten the same to suit. The length of the retractor projecting from the socket may be thus maintained constant for all lamps.

It is thus seen that I have provided a device which fulfills the several objects of the

invention, and is well adapted to meet the 65 conditions of practical use.

It is to be understood that within the scope of the invention, the term "lamp base" includes plugs and similar screw devices.

The invention contemplates the obvious application of the locking member 25 to all male and female interengaging screw members, as the full equivalent of the lamp base and socket.

I claim:

1. In combination, a lamp base, a socket having screw engagement therewith, and a device to lock the lamp base against removal from the socket, said socket having an outer metallic wall, a sleeve of insulation therein, and a contact shell in the said sleeve, said contact shell terminating in spaced relation to the outer end of the said sleeve, said device including an anchor portion engaged between the said shell and the said sleeve, an arm extending from said anchor portion and overlying the outer end of the contact shell, said arm having a locking member between the contact shell and the lamp base, said locking member extending angularly from the arm in the general direction of the axis of the lamp base, said member having its opposite edges sharp, said edges lying along an angle with the tangent to the lamp base to cause the said edges to bite into the lamp base and the contact shell to prevent removal of the lamp, and means to spring said arm to move the locking member out of engagement between the lamp base and the contact shell.

2. In combination, a lamp base, a socket having screw engagement therewith, and a device to lock the lamp base against removal from the socket, said socket having an outer metallic wall, a sleeve of insulation therein, and a contact shell in the said sleeve, said contact shell terminating in spaced relation to the outer end of the said sleeve, said device including an anchor portion engaged between the said shell and the said sleeve, an arm extending from said anchor portion and overlying the outer end of the contact shell, said arm having a locking member between the contact shell and the lamp base, said locking member extending angularly from the arm in the general direction of the axis of the lamp base, said member having its opposite edges sharp, said edges lying along an angle with the tangent to the lamp base to cause the said edges to bite into the lamp base and the contact shell to prevent removal of the lamp.

3. The combination as set forth in claim 1, wherein said device is made of a single piece of flat sheet metal.

4. The combination as set forth in claim 1, wherein said device is made of a piece of flat sheet metal, and a plurality of anchor portions are provided affording engagement over a large angle, said portions being connected by

an arcuate member, said arm being of arcuate form and extending with the locking member in proximity to the end anchor portion.

5. As an article of manufacture, a device for locking a lamp base against unscrewing from a socket, said device including an arcuate anchor member, an arcuate arm extending from one end of the anchor member and having substantially the same axis, a locking member projecting from the free end of said arm in the direction of said axis, said locking member having opposite edges formed to constitute cutting edges, said cutting edges lying at an angle with the tangent to the arm to bite into the lamp base and into the socket.

10 6. As an article of manufacture, a device for locking a lamp base against unscrewing from a socket contact shell, said device including an arcuate carrier member and a locking member, said locking member having its opposite edges formed to constitute cutting edges lying at an angle with the tangent to the carrier member.

15 7. As an article of manufacture, a device for locking a lamp base against unscrewing from a socket, said device including an arcuate carrier member, and a substantially flat narrow locking member made of thin material, said locking member having its opposite edges constituting cutting edges lying at an angle with the tangent to the carrier member.

20 8. As an article of manufacture, a device for locking a lamp base against unscrewing from a socket, said device including arcuate carrier means, and a narrow locking member made of thin metal, said locking member extending substantially in the direction of the axis of said carrier means and having its opposite edges constituting cutting edges, said cutting edges lying at an angle with the tangent to the carrier means to bite into the lamp base and the socket.

25 9. In combination, a lamp base, a socket having screw engagement with the lamp base, and a device to lock the lamp base against removal from the socket, said device including a narrow locking member of thin material lying between the lamp base and the wall of the socket, said locking member having its opposite edges lying along an angle with the tangent to the socket constituting cutting edges, one of the edges biting into the lamp base and the other into the wall of the socket.

30 10. In combination, a lamp base, a socket having screw engagement therewith, and a device to lock the lamp base against removal from the socket, said device being made of a piece of thin sheet metal, said device having arcuate anchor means lying between the lamp

base and the wall of the socket, and a locking member between the lamp base and the contact shell of the socket, said locking member being of narrow form and extending in the general direction of the axis of the said anchor means, said locking member having opposite cutting edges lying along an angle to bite into the lamp base and into the contact shell.

35 11. In combination, a lamp base, a socket having screw engagement therewith, and a device to lock the lamp base against removal from the socket, said socket having a contact shell, said device having a narrow locking member between the lamp base and the contact shell, said locking member extending in the general direction of the axis of the lamp base, and resilient means carrying said locking member, said locking member having cutting portions angularly disposed to bite into the lamp base and socket.

40 12. In combination, a lamp base, a socket having screw engagement therewith, and a device to lock the lamp base against removal from the socket, said socket having a contact shell, said device having a narrow locking member between the lamp base and the contact shell, said member having angularly disposed cutting edges to bite into the socket and lamp base, said locking member extending in the general direction of the axis of the lamp base, and carrier means for said locking member.

45 13. In combination, a lamp base, a socket having a contact shell having screw engagement with the lamp base, and means between the lamp base and the contact shell having angularly disposed edges biting into the lamp base and into the contact shell, said biting action being made effective on attempting to unscrew the lamp base from the socket.

50 14. A construction as set forth in claim 13, wherein the first mentioned means is of ogee form to provide the said edges.

55 15. The combination with male and female interengaging screw members, of a narrow locking member made of thin material, said locking member lying between the screw walls of the said interengaging screw members, said locking member having its opposite edges lying along an angle with the tangent to the said interengaging members to cause said edges to bite into said interengaging members to prevent unscrewing of the same, and means to move the locking member from the space between the screw walls of the said interengaging members to permit same to be unscrewed.

In testimony whereof I affix my signature.
ROBERT A. MOORE.
